UNITED STATES PATENT OFFICE

JOHN G. MCFADDEN, OF CAMP HOLABIRD, MARYLAND

CYLINDER LAPPI NG TOOL

Application filed January 25, 1929. Serial No. 334,988.

This invention relates to improvements in lapping or grinding tools and relates more particularly to tools for lapping or grinding the interior working surface of cylinders, barrels, etc.

The primary object of the invention is to provide a tool which may be operated by hand or by a suitable prime mover for the purpose of lapping or grinding the interior working surface of a cylinder, or the like, the said tool being effective for removing scratches, scars, or the like from said working surfaces and for rendering the said cylinder truly circular.

A further object of the invention is to provide a tool of very simple construction; one which may be manufactured at a very nominal cost, and one which will be exceedingly effective in operation notwithstanding the simplicity of design.

Other objects and advantages of the invention will be apparent during the course of the following description:

In the accompanying drawings forming a part of this specification and in which like numerals are employed to designate like parts throughout the same,

Figure 1 is a side elevational view of the lapping or grinding tool embodying this invention, the said tool being illustrated in position within the cylinder, or the like,

Figure 2 is end elevational view looking in the direction of the arrow lines 2-2 on Fig. 1,

Figure 3 is a longitudinal sectional view taken on line 3-3 of Fig. 2,

Figure 4 is a sectional view similar to Fig. 3 but illustrates the lapping or grinding segments of the tool retracted for permitting the latter to be positioned within a cylinder, or the like which is to be lapped or ground,

Figure 5 is a transverse sectional view taken on line 5-5 of Fig. 4,

Figure 6 is a transverse sectional view of a protector employed for shielding the working surfaces of the lapping segments when the tool is not in use, and

Figure 7 illustrates the protector in position upon the tool.

The device, when briefly described, includes an operating rod or shank A upon

which is mounted, in a suitable manner, the lapping or grinding segments B. These segments are intended to be retracted and held in such position while the tool is being inserted into the bore of a cylinder for the purpose of lapping or grinding the latter. Expanding elements C are employed for yieldably forcing the segments B into their operative positions in grinding or lapping relation with respect to the working surface D of a cylinder, or the like. For the purpose of insuring proper movement of the segments B when being expanded or contracted, guiding elements E are provided. These elements E also act as driving connections between the segments and the shank A. In certain cylinders, it becomes necessary, or it is considered advisable, to employ a reduced portion, such as designated by the character (d), as a guide for the tool during the lapping or grinding operation. To utilize such reduced portion (d), a guiding sleeve F is slidably associated with the extended end portion (a) of the shank A.

The above brief description is believed to be sufficient to convey a general understanding of the construction and operation of the tool embodying this invention. However, for the purpose of completely disclosing all of the details of the device, the following specific description is given:

The various figures are believed to disclose what is now considered as a preferred embodiment of the invention, and in this embodiment, the shank A of the tool is formed with a squared end 10 by means of which the said shank may be operatively connected to a brace or other suitable driving means. The said shank preferably is round in section and has secured thereto, at a suitable point within the length of the same, a sleeve 11. One end of the sleeve is provided with an annular groove 12 for receiving the edge of a central aperture 13 formed in a washer 14 adapted to be securely and immovably held with respect to the sleeve by having the extremity 15 of the sleeve peened or riveted against the fixed washer 14. The remaining end of the sleeve

is externally screw threaded at 16 for a purpose to be disclosed at a later point.

The guiding elements E take the form of round rods 17 which are arranged at right angles with respect to each other and pass through similarly arranged openings 18 and 19 formed in the sleeve and shank 11 and 10 respectively. It will be noted that these guiding pins 17 are spaced longitudinally 10 of the shank A. It has been stated above that the sleeve 11 is suitably secured to the shank A. The guiding elements E perform the additional function of acting as connectors between the sleeve and shank to cause the 15 sleeve to rotate and reciprocate axially with the shank and to prevent relative movement of the sleeve with respect to the shank.

Any desired number of segments B may be provided but in the preferred embodiment 20 of the invention, four are illustrated. When expanded, the peripheral surfaces 20 of the segments are intended to form collectively a true circle which corresponds in diameter with the new or final diameter of the working 25 surface of the cylinder after having been lapped or ground to the extent desired. Each sector is provided with parallel faces 21 and inwardly converging faces 22 which are arranged at right angles with respect to the 30 faces 21. The faces 22 of adjacent segments are spaced with respect to each other when the segments are expanded into working engagement with the interior of a cylinder. Fig. 5 discloses these same faces substantially 35 in contact with each other, which relative positioning occurs when the segments are retracted.

Each sector is provided with an axial socket 23 for receiving an end of a guiding 40 element E. The sockets 23 are of a suitable length to permit of desired expansion and contraction of the segments relative to their respective guiding elements. Each sector furthermore is provided with a relatively 45 large socket 24 arranged in parallelism with the socket 23, as best illustrated in Figs. 3 and 4. The sockets 24 are each designed to receive a spring 25 which bears at one end against the sleeve 11 and at its other end against the closed end of the socket 24. It 50 will be noted, by examining Fig. 5, that the springs for diametrically opposite segments are arranged in axial alignment with respect to the guiding element for the remaining two segments but are positioned in the same plane 55 with said element.

One face 21 of each segment slidably engages the fixed washer 14. An adjustable washer 26 encircles the sleeve 11 and bears 60 against the remaining face 21 of each of the segments. For the purpose of varying the force of engagement of the washer 26 with the segments B, a nut 27 is mounted upon the threaded portion 16 of the sleeve 11.

Some cylinders are provided with reduced

bore portions, such as designated by the character (d). When such cylinders are to be lapped or ground, a guiding element F is employed and takes the form of a sleeve having a tapered outer face 28 and a bore 29. The guide may be driven into the reduced bore portion (d) from the exterior of the cylinder for frictionally holding the guide with respect to the cylinder. The extension or outer end portion (a) of the shank A is slidably positioned within the bore 29 of the guide. 70

For the purpose of preventing the highly polished and perfectly tooled peripheral surfaces 20 of the segments from becoming scarred or damaged while the tool is not in use, a soft flexible band 30 is provided. This band may be made of any desired material, such as leather, rubber, or even soft metal. The band 30 may be of a proper size to encircle the segments G when in their expanded or contracted condition. Fig. 7 discloses the band encircling the segments while the latter are expanded. 80

The operation of this lapping or grinding tool may be described as follows: The cylinder to be lapped or ground is arranged in an accessible manner with respect to the person intending to operate the tool. The segments B then should be compressed or moved inwardly into the position illustrated in Fig. 5. The nut 27 then should be threaded along the sleeve 11 for forcing the washer 26 into tight engagement with all of the segments whereby the latter will be securely held between the two washers 14 and 26. After so conditioning the tool, a suitable lapping or grinding compound should be placed or spread upon the peripheral surfaces 20 of the segments. The tool then should be positioned with respect to the cylinder so that the segments are arranged within the bore of the cylinder and adjacent one end of the latter, or as best illustrated in Fig. 4. After so positioning the tool, the nut 27 should be adjusted upon the sleeve 11 for releasing its pressure upon the washer 26 whereupon the springs 25 will expand the segments to place their working surfaces 20, with the superimposed lapping or grinding compound, in engagement with the bore D of the cylinder. By then reciprocating or oscillating the shank A with respect to the cylinder, the desired lapping operation will be accomplished. This action should continue until the interior working surface of the cylinder has reached the desired degree of perfection. 90

It is to be understood that the form of this invention herewith shown and described is to be taken as a preferred example of the same, and that various changes in the shape, size, and arrangement of parts may be resorted to without departing from the spirit of the 100 110 120 130

invention or the scope of the subjoined claims.

Having thus described the invention, I claim:

5 1. A tool of the type described comprising a shank, a sleeve positioned upon the shank, radially extending guiding pins offset in angular relation to each other passing through the sleeve and the shank, a stationary washer secured to the sleeve, a second washer adjustable axially of the sleeve, segmental sections positioned between said washers and guided by said pins, means for yieldably forcing the segments radially of said shank, 10 and means for moving the washers toward each other to retain the segments in any desired adjusted position.

.2. A tool of the class described comprising a shank, a sleeve positioned upon the shank, 20 radially extending guide pins offset in angular relation to each other passing through said sleeve and shank, a stationary washer secured to said sleeve, a second washer adjustable axially of said sleeve, a plurality of 25 interchangeable segments positioned between the washers and guided by said pins, means for yieldably forcing the segments radially of said shank, and means for moving the washers toward each other to retain the segments in any desired 30 adjusted position with respect to the shank.

3. A tool of the class described comprising a shank, radially extending guide pins offset in angular relation to each other and passing 35 through the shank, a stationary washer secured to the shank, a second washer adjustable axially of the shank, a plurality of interchangeable segments positioned between the washers and guided by said pins, a plurality 40 of compression springs seated in suitable openings in the segments for forcing said segments radially of the shank, and means for moving the washers toward each other to retain the segments in any desired 45 adjusted position with respect to the shank.

In testimony whereof, I have hereunto set my signature.

JOHN G. McFADDEN.
